C. CHISHOLM

UNDERSCORING DEVICE FOR PRINTING FORMS

Filed Jan. 26, 1925

FIG. -1

FIG. -2

FIG. -3

Inventor

Clifton Chisholm,

By
Balie Macklin, Frederick, Texas, Attorney

UNITED STATES PATENT OFFICE.

CLIFTON CHISHOLM, OF CLEVELAND, OHIO, ASSIGNOR TO THE AMERICAN MULTIGRAPH COMPANY, OF CLEVELAND, OHIO, A CORPORATION OF OHIO.

UNDERSCORING DEVICE FOR PRINTING FORMS.

Application filed January 26, 1925. Serial No. 4,764.

To all whom it may concern:

Be it known that I, CLIFTON CHISHOLM, a citizen of the United States, residing at Cleveland, in the county of Cuyahoga and State of Ohio, have invented a certain new and useful Improvement in an Underscoring Device for Printing Forms, of which the following is a full, clear, and exact description, reference being had to the accompanying drawings.

My prior Patent No. 1,438,580 granted December 12, 1922, shows and claims a printing form comprising a holder having rows of upstanding projections thereon, and flanged embossed printing strips resting on the projections and having their flanges extending behind them. By that means I am enabled to very readily carry a page form which may be mounted on a rotary printing drum. It is frequently desirable in printing from such a form to print horizontal rule lines between rows of characters, either in underscoring certain words of the printing matter or in making up ruled forms. The object of the present invention is to provide a rule or underscoring member adapted to be readily mounted on a form of the kind described and print rule lines parallel with the type lines. I have found that I can accomplish the desired horizontal ruling by providing a rule which is adapted to be mounted between successive embossed strips and rest on the holder between the strips, standing with its surface the same printing height as the characters on the strips. By enlarging the lower portion of such rule so that it engages the inwardly inclined undersides of the flanged strips I prevent the rule moving radially of the form, and thus maintain it in place. The friction of the rule with the holder and the adjacent embossed strips is outwardly sufficient to prevent the rule shifting longitudinally, though suitable stopping clips or plugs may be inserted at the ends of the rule if desired.

My invention comprises the combination with the holder and printing strips, of a rule mounted between adjacent strips and resting against the holder. It comprises also the feature of an enlarged bottom portion of the rule engaging the under sides of the strip flanges; also the more particular embodiment of the invention illustrated in the

drawing and hereinafter specifically described.

In the drawing, Fig. 1 is an end view of a flexible blanket made of sheet metal and having parallel rows of upstanding projections overlain by embossed flanged strips between certain of which my rules are shown; Fig. 2 is a perspective of the rule alone; Fig. 3 is a perspective of a portion of the blanket with printing strips thereon and one of the rules in place between the adjacent strips. The three views are on different scales.

In Figs. 1 and 3, A represents a suitable flexible blanket of metal, adapted to be held in any suitable manner on a rotary printing drum. Stamped up from this blanket are parallel rows of projections with overhanging edges. I have shown the projections in the form of raised buttons a, as claimed in Patent No. 1,438,584 of William J. Demming, and I have shown between these buttons raised corrugations a', as claimed in Patent No. 1,438,582 of B. J. Craig. The printing strips designated B are sheet metal members having upwardly stamped embossed characters b and having their edges b' flanged downwardly and inwardly. Such strips rest on a row of buttons a and corrugations a', while the flanges b' extend beneath the overhanging edges of the buttons a.

My underscoring strip C, shown in perspective in Fig. 2, comprises a single metal member adapted for mounting between adjacent embossed strips B. This underscoring strip has a parallel-sided upper portion c narrow enough to stand between the most proximate portions of adjacent printing strips while beneath this is an enlarged portion c' substantially triangular in cross-section, which occupies the space between adjacent flanges b' of the strips, substantially filling such space. The total height of the rule strip is such that when the bottom of the strip rests on the blanket, the top of the strip is in the same printing plane, or cylindrical surface, as the printing characters.

While I have shown my rule as mounted on a curved blanket adapted to be carried on a drum, the rule may be used on a flat blanket. In either case the upper portion of the rule is made narrow enough to slide into the available space between adjacent

2
printing strips, while the base portions are large enough to substantially fill the available space between the flanges of adjacent strips and the blanket. Accordingly though 5 these rules may be readily slid longitudinally into place, the friction against the blanket and printing strips is sufficient, if the rule has the preferred cross-sectional dimensions, to prevent it being inadvertently 10 shifted from position.

Having thus described my invention, I claim:

1. The combination, with a holder having raised portions thereon and printing strips 15 overlying such portions, of a rule mounted between the strips and resting on the holder between the raised portions thereof.

2. The combination of a holder having raised projections, printing strips overlying 20 the projections, and a rule mounted between the strips and resting on the holder and provided with means for holding itself in place.

3. The combination of a form holder, 25 flanged printing strips mounted thereon, and a rule strip mounted between adjacent embossed strips and engaging the flanges thereof and resting at its inner edge against the holder.

4. The combination with a form holder 30 having raised overhanging projections thereon, of embossed flanged printing strips mounted on the projections with their flanges extending beneath the overhanging portions thereof, and a rule strip mounted between 35 adjacent embossed strips and engaging the underface of flanges thereof and resting at its base against the holder.

5. The combination of a sheet metal form holder having stamped-up buttons arranged 40 in parallel rows, the edges of the buttons at the opposite sides of the row being above the body of the holder, embossed printing strips overlying the buttons and having flanged edges extending beneath them, and 45 a rule strip standing between adjacent em-

bossed strips and resting at its base on the holder

6. The combination of a flexible blanket held in arcuate form and having rows of up-standing embossed printing strips overlying 50 the projections and having flanged edges extending beneath them, and a rule strip standing between and bearing against the flanges of adjacent embossed strips and resting 55 at its base on the flexible blanket.

7. The combination with a form holder and printing strips mounted thereon and having converging edge flanges, and a rule strip standing between adjacent printing strips and having its base portion laterally 60 extended to engage the under faces of adjacent flanges.

8. The combination with a form holder, and printing strips mounted thereon and having converging edge flanges and a rule 65 strip between adjacent printing strips and having a complementarily diverging base portion.

9. The combination of a sheet metal blanket having struck-up projections thereon, 70 embossed printing strips resting on the projections and having converging edged flanges extending beneath the projections and a rule strip between adjacent printing strips resting 75 on the blanket and having the base portion made substantially triangular in cross-section to extend beneath and engage the underhanging flanges of adjacent printing strips.

10. As a new article of manufacture, a 80 rule strip having an upper portion in the form of a parallel sided narrow blade and a lower portion in the form of a bar substantially triangular in cross-section, the lower edge of the blade portion merging 85 with the apex of the triangular portion.

In testimony whereof, I hereunto affix my signature.

CLIFTON CHISHOLM.
